Specification for Design.

Patented Aug. 2, 1921.

Application filed December 22, 1920. Serial No. 432,619. Term of patent 7 years.

To all whom it may concern:

Be it known that I, LESTER R. WELLMAN, a citizen of the United States, residing at Chicago, in the county of Cook and State of Illinois, have invented a new, original, and ornamental Design for a Ceiling-Holder, of which the following is the specification, reference being had to the accompanying drawing, forming part thereof.

Fig. 2 is a side elevation of the same.

I claim:

The ornamental design for a ceiling holder, as shown.

LESTER R. WELLMAN.
